UNITED STATES PATENT OFFICE.

JOHN FISHER, OF LOS ANGELES, CALIFORNIA.

ECCENTRIC HINGE FOR MOLDING FLASKS.

1,416,629.

Specification of Letters Patent. Patented May 16, 1922.

Application filed February 21, 1921. Serial No. 446,792.

To all whom it may concern:

Be it known that I, JOHN FISHER, a citizen of the United States, residing at Los Angeles, in the county of Los Angeles and State of California, have invented new and useful Improvements in Eccentric Hinges for Molding Flasks, of which the following is a specification.

This invention is a hinge connection for 10 molding flasks and the like so arranged as to vary the axis of the hinge connection, in order to properly position the same with relation to the cope and drag of the flask, when the pattern plate is in position between the 15 cope and drag as well as when the pattern plate has been removed. By the arrangement of such a hinge connection the cope and drag may be readily swung apart so as to permit removal of the pattern plate, and as 20 readily swung together again in order to form the mold ready to receive the metal, and as a consequence there will be a great saving of time and energy.

The invention will be readily understood 25 from the following description of the accompanying drawings, in which—

Figure 1 is a perspective view of the cope of a mold having the improved hinge connection.

30 Fig. 2 is a similar view of the drag thereof. Fig. 3 is a similar view showing the cope and drag in position with a pattern plate between the same.

Fig. 4 is a side elevation of one of the 35 hinge connections showing the position of the same when the pattern plate is between the cope and drag.

Fig. 5 is a similar view showing the position of the hinge connection when the pattern 40 plate is removed.

Fig. 6 is a longitudinal section on the line 6—6 of Fig. 4.

In the drawings I have shown the improved hinge connection as employed in connection with a molding flask including a usual cope 1 and a drag 2, the latter being provided with upwardly projecting guide pins 3 co-operating with guide lugs 4 formed upon the cope. A pattern plate 5 is adapted 50 to be received between the cope and the drag and is provided with lugs 6 through which pins 3 are adapted to be received, so as to be engaged by guide lugs 4 and thus accurately position the cope, pattern plate and drag 55 relative to one another.

As an instance of this arrangement hinge brackets 7 are provided upon one side of the cope and are provided with projecting hinge lugs 8 having upwardly extending bearing slots 9 in their ends. Hinge brackets 10 are 60 provided upon the drag in alignment with bracket 7 and are formed with projecting hinge lugs 11 spaced from one another and having aligned bearing apertures 12 in their ends. A bearing rod 14 is journaled at its 65 respective ends in the bearing lugs of the respective hinges, and the portions of this rod between the bearing lugs 11 of each hinge form eccentric pintles 13 of reduced diameter and adapted to be received in the bearing 70 slots 9 of hinge lugs 8.

By this arrangement it will be seen that rotation of the bearing rod 14 will cause a shifting of the axis of the hinge connection thus provided. In practice the parts are so 75 arranged that the shifting of the axis of the hinge connection, which may be obtained, will be equal to the thickness of pattern plate 5 adapted to be received between the cope and the drag. The hinge connection is 80 adjusted so as to space the cope and the drag, and when the pattern plate is in position, the cope may be swung open for removal of the plate. After the pattern plate has been removed, rod 14 is rotated so as to 85 adjust the hinge connection and thereby cause the cope to fit tightly upon the drag when subsequently swung closed, in order to form the mold ready to receive the metal.

Rod 14 is adapted to be locked in its adjusted positions for varying the position of the axis of the hinge connection, and for this purpose pins 16 extend from the respective ends of the rod at circumferentially spaced points. Stops 17 project from the outside 90 hinge lugs 11 of the respective hinge connections, and the pins 16 are so arranged that when engaged by the respective adjacent stops the rod 14 will be locked against rotation in one or the other of its adjusted 95 positions.

In order to provide for the engaging and disengaging of the pins 16 and the stops, the rod 14 is preferably arranged for slight longitudinal movement of the pins and stops 105 and so positioned that when the rod is shifted in one direction axially, one of the pins will be engaged by this stop, while the opposite pin will have moved beyond its stop, and in similar manner when the rod is shift- 110

ed in the opposite direction, the first pin will be disengaged while the second pin will be engaged by its stop.

Various changes may be made without departing from the spirit of the invention as claimed.

What is claimed is:

1. A molding flask comprising a cope and drag having a separable hinge connection for adjustment of the axis thereof relative to the flask, said adjusting means including a pivot rod having locking pins, and means arranged to be engaged by the respective pins in order to lock the hinge connection in adjusted positions.

2. A molding flask comprising a cope and drag having a hinge connection arranged for adjustment of the axis thereof relative to the flask, and means for locking the hinge connection in adjusted positions.

3. A molding flask comprising a cope and drag having hinge connections eccentrically arranged so as to adjust the axis of said connection relative to the flask, said eccentric adjustment including a pivot rod extending from one hinge connection to the other.

In testimony whereof I have signed my name to this specification.

JOHN FISHER.
